JOHN H. BIERMANN. [L. S.]

UNITED STATES PATENT OFFICE.

JOHN H. BIERMANN, OF HOBOKEN, NEW JERSEY.

DESIGN FOR A BOX.

SPECIFICATION forming part of Design No. 17,878, dated November 15, 1887.

Application filed October 6, 1887. Serial No. 251,670. Term of patent 3½ years.

To all whom it may concern:

Be it known that I, JOHN H. BIERMANN, a subject of the King of Prussia, residing at Hoboken, in the county of Hudson and State of New Jersey, have invented and produced 5 a new and original Design for Boxes, of which the following is a specification, reference being had to the accompanying drawing.

This invention relates to a design for a box, 10 as set forth in the following specification and claim and illustrated in the accompanying illustration, which represents a perspective view of a box containing my design.

In the drawing, the letter A indicates the 15 box-lid, said lid being hemispherical in shape. B indicates the body of the box, which is formed with an extension, C. To the body B is secured a band or ribbon, D, having a bow-knot, E, at the front of the body B, and above 20 the knot E is secured a shield-like ornament, F. Lines or bands G are caused to pass from the central upper portion of the cover A toward the edge or periphery,

The line H indicates the circle of demarcation or separation between the cover A and 25 the body B of the box, the cover being ornamented by the quadrantal divisions separated by the lines G, the adjacent divisions being of contrasting color.

What I claim as new, and desire to secure 30 by Letters Patent, is—

The design for a box herein shown and described, the same consisting of the hemispherical cover A, having quadrantal divisions or pieces separated by lines G, the body B, having 35 an extension, C, the band D, having a knot, E, and a shield-like ornament, F, secured above said knot E, the body B and cover A being separated by a line of demarcation, H.

In testimony whereof I have hereunto set 40 my hand and seal in the presence of two subscribing witnesses.

JOHN H. BIERMANN. [L. S.]
